SWITCHBOARD

William M. Scott, Jr., Bryn Mawr, Pa., assignor,
by mesne assignments, to I-T-E Circuit Breaker
Company of Pennsylvania

Original application August 27, 1938, Serial No.
227,089. Divided and this application April 26,
1940, Serial No. 331,687

11 Claims. (Cl. 175—298)

My invention relates to switchboards for use with removable or truck-type circuit-breakers, and more particularly relates to disconnect arrangements providing for disengageable connection between the contacts of circuit-breakers and conductors or busses of switchboards.

In accordance with my invention, the stationary disconnect contacts of the switchboard, engaged by the complementary movable contacts of the circuit-breaker unit when in service position, are directly mounted upon or supported by the conductors or busses of the switchboard; preferably, upon each of the bus conductors is mounted a support for a plurality of disconnect contact elements having limited relative movements to accommodate misalignment or irregularity of the complementary disconnect contact structure of the circuit-breaker.

Further in accordance with my invention, each of the bus conductors is covered with insulation except where exposed for support of a disconnect contact structure, and where so exposed is within an insulated housing which also encloses the disconnect contact structure for that bus conductor; more particularly, a wall of the switchboard is provided with slots or openings, in alignment with the disconnect contacts in their respective housings, through which are introduced and withdrawn into and from service position the disconnect contacts of the circuit-breaker unit.

Further in accordance with my invention, the switchboard and the circuit-breaker unit having overlapping wings or wall elements which prevent access to the disconnect contacts on the circuit-breaker unit until after the unit has been so far withdrawn from its service position that its disconnect contacts have moved out of the housings enclosing the disconnect contacts on the bus conductors.

My invention further resides in the features of combination, construction and arrangement hereinafter described.

This application is a division of my co-pending application Serial No. 227,089 filed August 27, 1938 now Patent No. 2,258,150.

For an understanding of my invention, reference is to be had to the accompanying drawings in which:

Fig. 1 is a front perspective view of a switchboard with a plurality of truck-type circuit breakers in service position;

Fig. 2 is a perspective view of the rear of the switchboard of Fig. 1 with some of its panels removed;

Fig. 3 is a perspective view of part of the switch-

board of Fig. 1 with the truck units completely withdrawn and not shown;

Fig. 4 is a side view in section of one of the truck units of Fig. 1 and of its associated switchboard unit;

Fig. 5 is a perspective view on enlarged scale and with parts broken away of a disconnect arrangement shown in Fig. 4;

Figs. 6 and 7 are plan views in section illustrative of the relative positions of the truck and switchboard units when their disconnect contacts are engaged, Fig. 6, and disengaged, Fig. 7;

Fig. 8 is a rear view in perspective of the truck unit of Fig. 4.

Referring to Fig. 1, the switchboard SB is a rectangular metal-clad structure containing bus bars, cable connections, and one or more truck or withdrawal type circuit breakers B1—B6. The stationary structure S, Figs. 2 and 3, of the switchboard comprises units S1—S6, corresponding in number with the circuit breakers, suitably mounted in alignment with each other.

The ends E, E of the switchboard are suitably reinforced steel panels attached to the end units S1, S6 and are substantially wider than the side panels of the units. Each of the units S1—S6 consists of three compartments vertically aligned, individually covered with removable steel panels, and separated or sealed by horizontal steel barriers. Since all units are, or may be similar in construction, only one of them need be described. Referring to Fig. 4, the uppermost compartments 1 and 1a, of a unit S, exemplary of any of units S1—S6, are sealed from the next lower compartment 2 by the horizontal steel barrier 3; the upper wall 4 of the compartments 1, 1a is a steel plate forming the top of the unit; the rear wall of the compartment 1 is the removable steel cover plate 5; and the sides of the compartment 1 are formed by side plates 6 extending from top to bottom of the unit. The steel partition 7 isolates the two compartments 1 and 1a from each other.

The upper compartments 1, 1a contain auxiliary apparatus such as potential transformers

PT, relays, and wiring from control and signal contacts 8 which are suitably mounted on the under side of that portion of the bottom of compartment or duct 1a which projects beyond the front wall of compartment 2. Other auxiliary apparatus as meters M, control switches and the like, may be mounted upon the rear face (Fig. 4) of panel 5 for observation or operation from the rear of the switchboard.

Within the compartment 2 are supported the three bus conductors 9, 9a, 9b each wrapped in

phenolic insulation, molded and cured and clamped in the impregnated maple blocks 10, 10a (Fig. 2) to withstand short-circuit stresses. To each tubular bus is directly attached a support 11 for disconnect contacts 12 whose purpose and construction are hereinafter described. Each of the disconnect contact assemblies for a bus conductor is enclosed in its individual housing 13 of insulating material. The rear wall of compartment 2 comprises the removable metal panel 14 and the front wall thereof comprises the upper part of the panel 15, of insulating material and in which there are three staggered slots 16 for permitting contacts 17 extending from the rear of the circuit-breaker unit B to pass through the panel into the similarly staggered disconnect housings 13. Thus, when the unit B is withdrawn, it is impossible for an attendant accidentally to touch any uninsulated parts at high potential.

The bottom compartment 18 of the unit S, whose rear face is closed by the removable steel panel 19, contains cable disconnect contacts, suitably encased in insulating housings 20, current transformers CT, and the outgoing cable connections therefrom. The housings 20 are supported, as by insulators 21 from the cross brace 22, in alignment to receive the contacts 23 which pass through slots 24 in the lower part of panel 15 from the rear of the breaker unit B. The duct 25 along the front face of compartment 18 may be used to encase the wires from the transformers CT to a protective relay or electromagnet hereinafter identified. Access to the interior of duct 25 may be had by removal of the steel panel 25a.

Extending from the front of each unit (S1—S6) are the rails 26 for guiding the wheels 27 of its associated circuit breaker unit (B1—B6), a pair of lugs 28 whose purpose will hereinafter be described, and a dust shield member 29 for the auxiliary contacts 8. The rails 26 extend upwardly from the steel base 30 from which also extends the tripping cam 31 whose purpose will hereinafter appear.

The steel base 30, comprising plates and structural members, extends the length of the switchboard and forms a foundation to which the units are secured.

Reverting to the arrangement providing for disengageable connection of the bus conductors with disconnect contacts 17 of the circuit-breaker unit B, the support 11 for the bus disconnect contacts 12 comprises two members 11a, 11b (Fig. 5) of metal which are clamped by bolts 32 directly to the bus conductor 9. From the front of member 11b extend the brackets 33 for supporting the pins 34, 35 upon which the upper and lower contacts 12 are respectively pivotally mounted. The upper and lower contacts 12 of each of the several groups shown in Fig. 5 are biased toward each other by a spring 36 which encircles a bar 37 through which loosely extend two yoke members.

The upper equalizing yoke 38 presses downwardly on the upper face of two adjacent upper contacts 12; a similar yoke (not shown) bears against the under faces of the corresponding pair of lower contacts 12. The pin 39 passes loosely through forward ends of all of the upper contacts 12 and similarly pin 40 passes loosely through the forward ends of all of the lower contacts 12. This contact construction, more fully described in United States Letters Patent #2,029,028 to Kneass et al., insures equal distribution of the

contact pressure between contacts 12 and 17 notwithstanding their appreciable misalignment.

The housing 13 which is assembled about the bus disconnect structure after the latter has been clamped to the bus conductor comprises two separable parts held together as by screws 41. Across the open front end of the housing extend two pivotally mounted shutters 42 of insulating material biased toward engagement with each other by springs 43. The gap between the forward edges of the shutters is in alignment with the corresponding slot 16, Fig. 4, in the panel 15. When the circuit-breaker unit B is pushed into position, each of the disconnect contacts 17 enters its corresponding slot 16, separates a pair of shutters 42, and slides between the upper and lower disconnect contacts 12. When the unit B is completely withdrawn, the shutters 42, 42 withdraw in each housing 13 close the corresponding panel slot 16 and preclude accidental contacts with the disconnect contacts 12.

As more apparent from Fig. 2, the bus conductors and live parts connected thereto are completely insulated and effectively isolated from each other. The bus conductors, as previously stated, are encased in insulation except within the insulating housings 13, and each disconnect contact assembly is within its individual housing 13 of insulation. When panel 14 is opened, there is, therefore, no possibility of accidental contact with any of the live parts within compartment 2. Moreover, as shown in Figs. 6 and 7, the sides 6, 6 of the unit S so far overlap the sides of the circuit-breaker unit B that it is not possible for an attendant to touch the contacts 17 until after the unit B has been so far withdrawn from the switchboard that contacts 17 are out of engagement with the live disconnect contacts 12.

Each of the truck units B1—B6, exemplified by unit B, Figs. 4 and 8, is a substantially rectangular structure formed by angle iron and sheet steel suitably joined as by welding. The door 44 which permits access to the circuit-breaker mechanism hereinafter described is provided near the top with a louvered opening 45 to permit escape of gases incident to circuit interruption and allow circulation of air for cooling. In the particular construction shown in Figs. 4 and 8, the top of the truck structure is closed by a sheet metal wall 46.

The circuit breaker and its operating mechanism is removable as a unit from the rear of the truck structure after it has been withdrawn from the switchboard. When the unit is in position, its wall 47 serves as the lower part of the rear wall of the upper or circuit-breaker compartment of the truck; the upper part of the rear wall of the truck compartment is an integral part of the truck structure.

The circuit breaker shown herein is a three-pole breaker but since the constructions of all three poles are similar, only one is described. Referring to Fig. 4, the upper main contact assembly 65 comprises a stud 66 which passes through the sleeves 67, 68 of insulating material. By tightening nut 70 on stud 66, the two sleeves 67, 68 are forced tightly against opposite sides of the vertical wall 47 of frame 51. Similarly, the lower main contact assembly 71 is mounted upon a stud 72 which passes through sleeves 73, 74 of insulating material. By tightening nut 76, the sleeves 73, 74 are clamped to opposite sides of the rear vertical wall of the frame 51.

The disconnect contacts 17, 23 are held to the

studs 66, 72 by the nuts 71, 78, respectively. The upper end of each of the disconnect contacts 17 is braced by an insulator 79, Fig. 8, to resist bending during insertion and withdrawal of the circuit-breaker unit B from the switchboard. The insulators 79 are secured to and project horizontally from the rear face of the upper part of the steel wall 47 of frame 51.

The main contact assemblies 65 and 71 are mechanically interconnected by the insulator 84 which resists forces, due to flow of heavy currents, tending to move assemblies away from each other. The insulator 85 mechanically connected to the frame member 86 of assembly 71 and to the base plate 48 of the unit frame 51 stiffens or supports the assembly 71 against forces or shocks incident to the opening and closing movements of the parts of the circuit breaker.

The upper main contact assembly, Fig. 4, comprises the main contact member 87, the auxiliary contact member 88, the arcing horn 89, the arcing tip 90, and the blowout coil 91. The auxiliary contact 88 is biased by a spring and connected by pigtail to the main contact. A pair of links on opposite sides of contacts 87, 88 support and guide the latter during its movement.

The arcing horn 89 is mechanically connected to the main contact 87 by bolts which pass through sleeves of insulating material and clamp the front and rear ends of the horn against the plates of insulating material.

One end of the blowout coil 91 wound upon core 102 is held in electrical connection with main contact 87 and the other terminal of the coil is held in electrical connection with the arcing horn structure. Electrical connection of the horn 89 with contact 87 except through the blowout coil is precluded by sleeves and plates of insulation. The coil is wound from heavy flat wire or ribbon covered with insulation resistant to the effects of high temperatures.

The lower main contact assembly 71, Fig. 4, comprises the stationary frame member 86 within which is pivotally mounted the movable frame member 103 connected by pigtail (not shown) to the stationary frame member and to the bridging contact member 105 loosely pivotally mounted in the movable frame member 103. To the upper end of movable frame member 103 is attached the arcing contact 115 which, when the circuit breaker is closed, (Fig. 4), engages both the auxiliary or shunt contact 88 and the movable arcing horn tip 90.

All of the operating mechanism for the circuit breaker is supported from the under face of the horizontal wall 48 of the frame 51 and the only connections between the movable contact structures and their operating mechanism are the rods 154 which are of insulation; the upper end of each rod 154 is received by a coupling member 155 pivotally connected to the movable frame 103 for the movable contact structure of one pole of the circuit breaker and the lower end of each rod 154 is received by a coupling member 156 pivotally connected to an operating arm 157 (Fig. 4). All of the operating arms 157 are secured to shaft 158 supported intermediate its ends by a pair of split bearings, not shown, one on each of the side plates 162.

The coil 160 which may be energized to effect closure of the circuit breaker is within a housing 161, Fig. 4, having two sides formed by steel plates 162 which serve as sides of the coil housing and as bearing plates for shafts of the operating mechanism, and also provide feet upon which the

circuit-breaker unit may rest when withdrawn from the truck.

The link 172 pivoted at its rear end to the front end of core 169 is provided with an elongated slot 173 which slidably receives the pivot pin 174 of the toggle links 175, 176. The upper end of toggle link 175 is pivotally connected by pin 178 to a bell-crank lever 179 whose pivot pin 180 provides a fixed axis for angular movement of lever 179. The ends of pin 180 are supported by plates 162.

The arm 181 of lever 179 is engageable near its free end by the latching member 182 secured to shaft 183 and biased to its latching position. 20 When the coil of a tripping magnet, not shown, is sufficiently energized, as upon occurrence of an overload, the movement of its armature rocks shaft 183 in counterclockwise direction to release the latch 182, whereupon powerful springs, not 25 shown, rock the shaft 158 to open the circuit breaker.

All of the stresses incident to opening and closure of the circuit breaker are confined to the frame 51 and are not transmitted from one operating part to another through the truck frame. Moreover, since the operating mechanism in its entirety is part of the circuit-breaker unit, it may readily be assembled and tested as a completely operative unit prior to mounting in the truck. Preferably the kinetic energy of the moving operating parts is absorbed by a friction brake B similar to that disclosed and claimed in co-pending application Serial No. 98,562.

The circuit breaker may be tripped manually by depressing the forward or handle end of lever 190 which is pivotally mounted within a housing or bracket 191 secured to the front end of the frame 51. The handle of lever 190, as shown in Figs. 1 and 4, projects through a slot 190a in the door 44 of the truck. When the handle is depressed the extension 192 of lever 190 engages the extension 193 of latch 182 to effect its release from arm 181 and so permit springs 189 to open the circuit breaker.

The circuit breaker may be reclosed manually by inserting a bar 194 through an opening 195 (Fig. 1) in the truck door and into the slot 196 of a disk 197 loosely mounted, between the sides of bracket 191, on the shaft 198. A link, not shown, connects the disk 197 to the toggle pin 174. After the bar 194 is so inserted, it is swung downwardly through an arc of about 90 degrees and so moves pin 174 to the left thus to rock the shaft 158 in clockwise direction to lift the rods 154 and so effect circuit-closing movement of the movable contacts of the circuit breaker. If an overload exists, the circuit-breaker cannot be held closed by bar 194 because when the latch 182 is released, the toggle collapses and aforesaid powerful springs are free to open the circuit breaker regardless of the position of disk 197. The construction and operation of the operating mechanism is similar to that disclosed and claimed in Reissue Patent No. 19,753 to H. C. Graves.

Preferably, the edge of disk 197, which is visible through opening 193 in the truck door 44 is colored or otherwise marked to indicate whether the circuit breaker is in open or closed circuit position. The disk 197 is biased to the

"open circuit" position so that it will move to that position when bar 194 is removed or released after tripping of the breaker during manual closure thereof. The biasing spring also restores the arm 181 to its latching position after tripping of the circuit breaker in readiness for the subsequent re-setting of the toggle incident to automatic or manual reclosure of the circuit breaker.

The bar 202 pivotally suspended from arm 157a on the operating shaft 158 of the circuit breaker is utilized to operate the auxiliary switches 203 mounted upon the panel 204 suitably mounted in the lower compartment of the truck. These switches may be used to operate signal lights or perform other control functions in accordance with the position of the circuit breaker.

From the tripping lever 190 is suspended the rod 201 which extends through the base of the truck in line with the cam 31 on the base 30 of the switchboard to trip the circuit breaker, if it be closed, as the truck is pushed into the switchboard to effect engagement of movable disconnect contacts 17 with the stationary disconnect contacts 12.

Each truck unit B1—B6 is locked in its innermost or normal position by a pair of racking bars 205 (Fig. 4) each having a hooked end which drops over and engages the pin 206 of one of the pair of abutment members 28 attached to the front face of each of the switchboard units S1—S6; the rear face of the hooked end is suitably sloped so that if it is down when the truck is pushed into the switchboard, the engagement of the sloping end with pin 206 causes the bar to lift and drop over the pin. 35 The other end of each bar 205 is pivotally connected to a crank arm secured to shaft 198 to which is secured a notched disk accessible through the opening 195 in the door 44 of the truck. The ends of this shaft are supported 40 in bearings 193a in brackets integral with frame 51.

The actuation of the notched disk to move the truck from its service position, in which the disconnect controls 17 connect the circuit-breaker 45 to the busses 9, 9a, 9b, to a test position in which said disconnect connects 17 are out of engagement with the stationary disconnect contacts 12, and from the test position to a wholly withdrawn position is fully described in my aforesaid co-pending application Serial No. 227,089. Other features of the disclosure not herein claimed are described and claimed in copending 55 divisional application Serial No. 251,500 filed January 18, 1939, Serial No. 331,507 filed April 25, 1940.

What I claim is:

1. The combination with a bus conductor, of an insulated housing extending transversely of and embracing a section of said conductor, and disconnect contact structure directly and detachably attached to and supported by said conductor within the housing and comprising structure determining the position of said housing with respect to said conductor and said contact structure.

2. The combination with a bus conductor, of a panel adjacent said conductor having a slot in alignment therewith, an insulated housing for embracing a section of said conductor and having an open end, and disconnect contact structure directly mounted on and supported solely by said conductor within said housing and comprising structure enforcing location of said housing with its open end presented to said slot.

3. A switchboard arrangement comprising the combination with a bus conductor, of an insulating housing, through ends of which said conductor extends, supported from said conductor and comprising separable parts assembled and disassembled about the conductor without dislocation thereof, insulation covering said conductor except for a short section exposed within said housing, and disconnect contact structure directly attached to said short section of exposed conductor within said housing and accessible by disassembly thereof.

4. A switchboard comprising a compartment, a plurality of bus conductors within said compartment, a plurality of individual insulated housings spaced from one another within said compartment and each comprising separable parts assembled about and supported by a short intermediate section of one of said conductors, insulation covering each of said conductors except within said housings, and a plurality of disconnect contact structures each directly attached to one of said conductors within its associated housing accessible by disassembly thereof, and comprising structure coacting with said associated housing to determine the position thereof with respect to the other of said housings in said compartment.

5. A switchboard having a compartment accessible from one side of the switchboard, a panel for preventing access to said compartment from the other side of said switchboard and having a plurality of slots, a plurality of bus conductors within said compartment, a plurality of insulated housings spaced from one another within said compartment and each embracing a short intermediate section of one of said conductors, insulation covering the conductors except within said housings, and a plurality of disconnect contact structures each directly attached to and supported by one of said conductors within its associated housing and comprising structure enforcing location of its associated housing with open end thereof presented to one of said slots.

6. A switchboard having a compartment, a plurality of bus conductors extending parallel to each other transversely of said compartment, a plurality of insulated housings staggered with respect to each other and each embracing a section of one of said conductors, disconnect contact structures each directly attached to one of said conductors within the associated housing, insulation covering each of said conductors except within said housings, and insulating panels each supporting said bus conductors and dividing said compartment into sub-compartments each containing not more than one of said housings.

7. A switchboard comprising a normally closed compartment accessible from one side of the switchboard and having slots in a panel comprising the opposite side of the switchboard, a plurality of conductors within said compartment, a plurality of insulated housings spaced from one another within said compartment each embracing a short intermediate section of one of said conductors and having its open end presented to one of said slots, insulation covering conductors except within said housings, and disconnect contact structures each directly attached to and supported by one of said conductors within the associated housing, and means for preventing accidental engagement with the disconnect contacts comprising movable structures mounted

at the open ends of the housings and biased to block said slots.

8. The combination with spaced supporting structures of insulation, bus conductors each extending through and supported by said spaced supporting structures, and disconnect contact structures, each supported directly by and electrically connected to one of said bus conductors and separated from another of the disconnect contact structures by one of said spaced supporting structures.

9. The combination with spaced supporting structures of insulation, bus conductors each extending through and supported by said spaced supporting structures, disconnect contact structures, each supported directly by and electrically connected to one of said bus conductors, insulation covering each of said conductors except where connected to its said disconnect contact structure, and insulated housings each supported by one of said bus conductors to enclose its disconnect contact structure and separated from another of said housings by one of said spaced supporting structures.

10. A switchboard comprising bus conductors supported within a compartment, a panel for said compartment, disconnect contact structures each directly attached to and supported by one

5 of said conductors, housings each supported by one of said conductors to enclose aforesaid disconnect contact structure mounted thereon and located by said contact structure with an open end presented to a slot in said panel, and shutter structure for each of said housings biased to close the open end thereof.

11. A switchboard having a compartment, a plurality of bus conductors extending substantially parallel to each other transversely of said compartment, a plurality of housings of insulating material staggered with respect to each other and each embracing a relatively short portion of one of said bus conductors, disconnect contact means comprising electrically conductive structures each attached to a different one of said bus conductors within its associated one of said housings, insulation for each of said bus conductors complementary to its insulation afforded by its associated housing in completion of electrical isolation within said compartment of each of said bus conductors, and insulating panels each supporting said bus conductors and jointly dividing said compartment into sub-compartments each containing not more than one of said housings.

15 20 25 WILLIAM M. SCOTT, JR.
